EDGAR A. ROCK, DECEASED, LATE OF NORFOLK, NEBRASKA, BY CAROLINE F. ROCK,
ADMINISTRATRIX, OF NORFOLK, NEBRASKA

APPARATUS FOR BENDING SMALL PIPES

Application filed March 30, 1929. Serial No. 351,271.

This invention relates to apparatus for bending small pipes, and more particularly to apparatus for use in bending the small copper conduits employed in domestic refrigerating apparatus in making installations of this refrigerating apparatus in the refrigerator.

As will be obvious from a consideration of such apparatus, there is frequently the necessity for making a short bend in one of the coil pipes or conduits of the refrigerating system while the system is in position upon the refrigerator and it will also be obvious that under such circumstances, the available space for insertion of a tool to accomplish this bending is restricted. Furthermore, it is often desirable to bend a pipe, the ends of which are secured, rendering it impossible to employ with the device many of the tools constructed for this purpose. A bend cannot be made forcible without some restraining device upon the pipe, as otherwise the pipe will widen transversely and flatten at the bend, thereby producing a stricture in the conduit which is extremely likely to interrupt proper flow therethrough.

Accordingly, an important object of the present invention is the provision of an apparatus which is so constructed that it may be assembled about the pipe which is to be bent for the bending operation, which is small and may accordingly be employed in close quarters and which is extremely light in weight, so that it may be readily transported in a tool kit or, if desired, in a coat pocket.

A further object of the invention is to produce a device of this character wherein the portion of the pipe at which the bend is being formed is always confined so that it may not widen transversely and is accordingly restricted against flattening.

These and other objects are attained by the construction shown in the accompanying drawing, wherein for the purpose of illustration is shown a preferred embodiment of the invention and wherein:

Figure 1 is a side elevation of a pipe bending tool constructed in accordance with the invention showing the same applied to a pipe

at the completion of the bending operation;

Figure 2 is a longitudinal sectional view through the bending apparatus illustrating the jaws in the position which they would occupy at the beginning of a bending operation and showing a second manner of applying the pressure bar thereto;

Figure 3 is a section on the line 3—3 of Figure 1;

What is claimed:

Referring now more particularly to the drawing, the numeral 10 generally designates a substantially L-shaped trough, the groove 11 of which is at the exterior of the angle of the trough and is deepened at its center or the apex of the bend, as indicated at 12. The side walls of the trough at one end have lugs 13 which are provided with coves 14 opening through the outer ends of the lugs for a purpose presently to appear.

The opposite ends of these trough walls have mounted thereon a pair of pivot elements 16 which are preferably located upon ears 17 formed upon these walls. The bottom of the trough at the reentrant angle is thickened, as indicated at 18, and in its outer face is formed with a shallow socket 19, the purpose of which will hereinafter appear.

An L-shaped bending bar 20 is provided, the inner face of which is formed with a shallow groove 21 extending from end to end thereof and about the end faces of the bar, as indicated at 22. The side faces of this bending bar at one end have mounted therein pivot elements 23 adapted to engage in the coves 14 of the ears 13 of the trough member and at the junction of the arms of this bar, a second pair of pivot elements 24 extends from opposite faces thereof.

In combination with the elements just described, there is provided a yoke comprising a cross bar or head 25 having extending therefrom a pair of parallel leg elements 26 spaced apart a distance such that they may receive the trough member therebetween.

The ends of these legs have hooks 27 for engagement with pivot elements 16 or 24 and directed through the head and having threaded engagement therewith is a pressure bar 28 having a lever handle 29 by means

of which it may be rotated. The inner end of this pressure bar has a reduced terminal 30 for engagement in the socket 19 of the trough member or in a socket 31 formed in the outer face of the bending bar 20 at the 5 opposite end thereof from the pivots 22.

In use of apparatus of this character, the trough member and bending bar are separated and placed upon opposite sides of the 10 pipe when the pivot members 23 are engaged in the coves 14 of the ears 13 of the trough member. The hooks 27 of the yoke are then engaged with the pivots 16 and the end of the pressure bar engaged in the socket 15 31 of the bending bar. The pressure bar 28 is then rotated so as to force the free end of the bending bar toward the free end of the trough member, this bending bar engaging the conduit and forcing it before it, so 20 that it is bent about the camber of the central portion of the bottom wall of the trough. The portion of the conduit in which the bend is being formed will lie between the side walls of the trough so that spreading of the 25 conduit is prevented at this time. To continue the bending and obtain the maximum bend available with this tool, the hooks of the yoke are disengaged from the pivots 16 and engaged with the pivots 24, and the end 30 of the pressure bar engaged in the socket 19. At this time, the pressure bar and trough may be brought to their fully closed positions, as illustrated in Figure 1.

It will be noted that the manner of connecting the yoke and its pressure bar to the sections of the bending tool effectually prevents separation of the elements of the tool. In other words, when the pressure bar is initially engaged, the pressure applied thereto tends to move the bending bar and trough 40 elements in opposite directions and applies its force in such manner that the pivots seat more firmly in the coves. The same is true when the secondary engagement is 45 made although, at this time, such provision is not necessary, due to the fact that the bend already formed in the pipe will institute a wedging action, tending to cause a movement of this character. Therefore, the tool sections while readily separable when not under pressure, tend to more firmly engage 50 when under pressure.

It will be obvious that a structure of this character may be very readily and cheaply 55 produced, may be made very light and accordingly conveniently portable and will be durable and efficient in service. It will also be obvious that the construction hereinbefore set forth is capable of a certain range of 60 change and modification without materially departing from the spirit of the invention and is accordingly not limited thereto except as hereinafter claimed.

What is claimed:

65 1. In a bending apparatus for use with

small pipes, an angular member having a trough formed in its cambered face, a similarly angled bending bar having a pipe receiving groove formed in its inner face, co-acting means at corresponding ends of the angular member and bending bar for detachably pivotally connecting the same to one another, the bending bar being movable into the trough of the bar, and means detachably engageable with one of said elements and having an adjustable pressure bar for engagement with the other of said elements for moving the free end of the bending bar toward and into the trough of said member. 70

2. A device as claimed in claim 1 wherein the means pivotally connecting the member and bending bar are detachable by movement of one of the elements in a given direction with relation to the other of the elements and the pressure bar applies its pressure in a direction tending to cause movement of the first named element in the opposite direction. 80

3. In a bending apparatus for use with small pipes, an angular member having a trough formed in its cambered face, a similarly angled bending bar having a pipe receiving groove formed in its inner face, co-acting means at corresponding ends of the angular member and bending bar for detachably pivotally connecting the same to one another, the bending bar being movable into the trough of the member, the member having a pair of pivot elements engaged with opposite side faces thereof at its free end, the bending bar at its free end and in its outer face having a socket, a yoke comprising a head and a pair of legs, the legs having hooks to detachably engage the pivots at the free end of the member, and a pressure bar adjustably directed through the head of the yoke and adapted to engage in the socket of the bending bar. 90

4. In a bending apparatus for use with small pipes, an angular member having a trough formed in its cambered face, a similarly angled bending bar having a pipe receiving groove formed in its inner face, co-acting means at corresponding ends of the angular member and bending bar for detachably pivotally connecting the same to one another, the bending bar being movable into the trough of the member, one of said elements having a pair of pivots at its side faces and at a point spaced from the pivotal connection of said elements, the other of said elements at a corresponding point and in its outer face having a socket, a yoke comprising a head and a pair of legs, the legs having hooks to detachably engage the pivots, and a pressure bar adjustably directed through the head of the yoke and adapted to engage in the socket of the other of the elements. 100

5. In a bending apparatus for use with small pipes, an angular member having a trough formed in its cambered face, a simi- 110

larly angled bending bar having a pipe receiving groove formed in its inner face, coacting means at corresponding ends of the angular member and bending bar for 5 detachably pivotally connecting the same to one another, the bending bar being movable into the trough of the member, one of said elements having secured to opposite side faces thereof at a point spaced 10 from such pivotal connection a pair of pivots, a yoke adapted to straddle the other of the elements and having hooks to detachably engage said pivots, and a pressure bar adjustable through the yoke to engage the outer 15 face of said other element.

6. A device as claimed in claim 3 wherein the means pivotally connecting the member and bending bar are detachable by movement of one of the elements in a given direction 20 with relation to the other of the elements and the pressure bar applies its pressure in a direction tending to cause movement of the first named element in the opposite direction.

25 In testimony whereof I hereunto affix my signature.
